UNITED STATES PATENT OFFICE

PETER J. POOL, OF CLERMONT, FLORIDA

TOBACCO PIPE

Application filed January 23, 1929. Serial No. 334,385.

My invention has for its object to provide a tobacco pipe wherein the saliva will be maintained separated from the oil of tobacco or entry of the saliva into the bowl of the pipe will be prevented in the ordinary use of the pipe and wherein the temperature of the smoke will be greatly reduced to produce a "cool smoke". Many forms of pipes have heretofore been produced with these objects in view, but the devices used have been enclosed in non-conductive walls with the result that after a number of "smokes" the evaporated oil soon collects on the separating means and contaminates the saliva which is sooner or later accidentally drawn back into the mouth of the user of the pipe. This is because the devices are confined within the area and enclosed within the walls of the pipe. By my invention, the smoke is cooled near the bowl end of the pipe and before its entrance into the bit end of the pipe. The cooling devices heretofore used being located within the confines of the walls of the pipe, which are heat insulated, prevents cooling of the smoke after the first few puffs, that is, the cooling means soon becomes as hot as the smoke itself. The cooling means of my invention is not confined within the walls of the pipe, but constitutes a continuation of the walls and is thus directly subject to the cooling temperature of the atmosphere and, being formed of an oil conductive material, it maintains a cool smoke and also maintains the saliva in the bit end of the pipe and prevents it from entering the bowl where it ordinarily separates the tobacco at the bottom of the bowl.

The invention may be contained in pipes that vary in their details and, to illustrate a practical application of the invention, I have selected a pipe containing the invention as an example of such structures and shall describe it hereinafter. The pipe selected is shown in the accompanying drawings.

Fig. 1 is a perspective view of the pipe.

Fig. 2 illustrates a longitudinal section through the pipe.

In the form of construction shown in the drawings, the usual pipe having a bowl 1 and a bit 2, are completely separated and interconnected by a sinuous or inverted U-shaped metallic member 3. The member 3 is, preferably, tubular in form and is inserted in the end of the stem 4 of the bowl 1 and in the end of the bit 2. Preferably, the tubular member 3 is formed of aluminum which is attractive in appearance and is also oil heat conductive. The ends of the inverted U-shaped member 3 extend, preferably, in axial alignment with the bit 2 and the stem 4 of the bowl. Thus, when the mouth piece 5 is inserted in the mouth and the smoke is drawn from the bowl 1, it enters the inverted U-shaped tubular member 3 and the oil of tobacco and other volatile parts are condensed or discharged upon the surface of one leg of the U formed by the passage-way 6 within the U-shaped tube that extends upwardly from the passage-ways of the stem of the bowl and the bit. Inasmuch as the tubular member 3 has its surfaces located on, or quite entirely in contact with the exterior atmosphere, the tubular member 3 is maintained substantially at the temperature of the atmosphere and although the pipe may be continuously used, yet the temperature of the tubular member 3 will rise but slightly. This keeps the smoke cool as it is drawn into the mouth of the user of the pipe. Preferably, the wall of the tubular member 3 is thin which aids in conducting the heat from the surface within the tubular member 3 to the surface exterior to the member 3. Also, the saliva will be kept in the bit 2 by the passage-way 6 which extends laterally with respect to the axis of the bit 2 and also the axis of the stem 4 where the ends of the tubular member connect with the bit 2 on the one end and the stem 4 of the bowl on the other.

I claim:

A pipe, having a bit and a bowl, an inverted U-shaped tubular member having progressively curved portions throughout its length, the ends of the U-shaped member located substantially in alignment with each other and extending in opposite directions, one end connected to the bowl and the other end connected to the bit.

10 In witness whereof I have hereunto signed my name to this specification.

PETER J. POOL.
